UNITED STATES PATENT OFFICE.

JOHN G. CALLAN, OF LYNN, MASSACHUSETTS, ASSIGNOR TO GENERAL ELECTRIC COMPANY, A CORPORATION OF NEW YORK.

GOVERNING MECHANISM FOR TURBINES.

No. 863,782.

Specification of Letters Patent.

Patented Aug. 20, 1907.

Application filed February 5, 1907. Serial No. 355,824.

To all whom it may concern.

Be it known that I, JOHN G. CALLAN, a citizen of the United States, residing at Lynn, county of Essex, State of Massachusetts, have invented certain new and useful 5 Improvements in Governing Mechanism for Turbines, of which the following is a specification.

My invention relates to governing mechanism for turbines, particularly those wherein a regulator or a valve of the puppet type or a plurality of separately or 10 successively actuated valves are employed to control the flow of motive fluid through the nozzles or other discharging devices of the turbine. It is desirable to control positively the position of such a regulator or valve from the time it leaves its seat until it reaches a 15 position where it is fully open and to hold the valve at points intermediate of its extreme position, locking it firmly at these points, so that the unbalanced forces cannot move it and thereby alter the speed of the turbine.

20 The object of my invention is to improve the construction of the governing mechanism, rendering it mechanically simple and of few parts and so constructing it that the regulator which is disconnected when it is either fully closed or fully open, may be rigidly 25 locked at various points between the open and closed positions, and is moved by a step-by-step movement, the extent of the steps being determined by a load responsive device.

The invention is preferably used in connection with 30 turbines, and is applicable to a single stage or to a multi-stage machine. Nozzles or other fluid discharging devices of any suitable character convert the pressure of the motive fluid into velocity and deliver it to the wheel buckets of the turbine, where the energy is 35 abstracted. The admission of fluid to the discharging devices is controlled by separately actuated valves, and one valve may control one nozzle passage or a number greater than one, as desired. Part of the valves are normally open, a part normally closed, and at 40 least one valve moves frequently for regulating purposes. The actuating mechanism for the valves is so arranged that the valves can open and close one after the other in response to variations in load, and so that one or more of the valves can be locked intermediate 45 the open and closed positions.

My invention will best be understood in connection with the accompanying drawings showing one embodiment thereof, in which

Figure 1 is an end elevation of the valve actuating mechanism; Fig. 2 is a longitudinal section of part of the mechanism shown in Fig. 1; Fig. 3 is a plan view of the mechanism shown in Fig. 1 as viewed on line 3—3; Fig. 4 is an end view partly broken away to illustrate the locking device; Fig. 5 a view showing the connection

between the actuating means and the valves; Fig. 6 a 55 diagrammatic view showing the relation of the governor and other elements of the device; Figs. 7 to 11, inclusive, diagrammatic views showing the relative positions of the parts during operation, and Figs. 12 and 13 views of a detail of the actuating mechanism. 60

In the embodiment of my invention shown in the drawings the general relation of the parts is shown in Fig. 6 in which 1 is a shaft driven from the turbine at a speed of about 100 revolutions a minute and carrying a crank 2 which, through the connecting rod 3, oscillates 65 a lever or actuator 4 loosely mounted upon or concentric with the valve actuating shaft 5 by means of which the valves are moved. The valve actuating shaft 5 carries bosses, 6, 6^a, each boss being provided with a tooth 7, 7^a, as shown in Fig. 5. It will be noted that 70 these teeth are set in a staggered relation to each other so as to form a spiral about the rock-shaft and coöperate with notches 8, 8^a, in slides 9, 9^a, rigidly attached to the stems 10, 10^a of the regulators or valves 11, by means of which the flow of fluid to the turbine is controlled, each 75 tooth and coöoperating notch forming an actuator for the respective valve and being so related that when the valve 11 is in either of its extreme positions, the tooth is out of engagement with the notch in the slide and the valve is entirely free from the valve actuating shaft 5. 80 When the valve is entirely open it is held in that position by the pressure of the fluid upon an effective area equal to that of the valve stem; when the valve is closed the pressure of the fluid holds it closed by acting upon an effective area equal to the difference between 85 the area of the valve and that of the valve stem.

As shown in Fig. 5, the relation of the teeth 7, 7^a, to each other is such that when the shaft 5 is rotating in the direction of the arrow, and the tooth 7 is leaving the notch 8, after having moved the slide 9 to fully open the 90 valve connected thereto, the tooth 7^a is just engaging the notch 8^a to move the slide 9^a and thereby open the valve connected to said slide. By this arrangement the valves are opened and closed successively.

The valve actuating shaft is driven by the engine actuated vibrating lever 4 by means of clutching mechanism which rigidly connects the lever 4 to the shaft 5, and the lever 4 has a range of movement sufficient to open or to close all the valves at one movement, if desired. As shown in Fig. 1, the lever 4 is provided with 100 dog-carrying arms 12, each of which carries at the outer end thereof pivots 13 on which sleeves 14 are loosely mounted. On the inner end of the sleeves, as shown in Fig. 3, are mounted dogs 15 and 16, the outer ends of the sleeves carrying riders 17 and 18 keyed thereto, while 105 springs 19 tend to move the dogs to engaging position. Any other means for rigidly connecting the dogs and riders can be used instead of the sleeves. A ratchet

disk 20 actuating the shaft 5 has teeth 21 engaged by the dogs 15 and 16 when the dogs are in operative position. A shield plate 22 mounted concentrically with the center of the arc described by the pivots 13, engages the 5 riders 17 and 18, and thereby moves the dogs to inoperative position out of engagement with the ratchet disk 20. The position of the shield plate and thereby the extent of movement given the ratchet disk 20 is determined by a governor responsive to changes in load on

10 the turbine.

The lever 4 oscillates through an arc of unvarying extent, and the shield plate 22 is so proportioned that when in the normal position, as shown in Fig. 1, it holds both dogs 15 and 16 in inoperative position 15 throughout their entire range of movement. If the speed decreases the shield plate is moved to the left in Fig. 1 and the rider 17 will drop off the end of the shield plate when the lever 4 moves to the right, thereby permitting the dog 15 to assume an operative position with relation to the ratchet disk 20. As the lever 20 4 starts back to the left, the dog 15 will engage one of the teeth 21, thereby rotating the ratchet disk 20 and shaft 5 clockwise until the rider 17 encounters the edge of the shield plate 22 and disengages the dog from the 25 ratchet tooth, and causing the partial opening of one valve or the opening of one or more valves, depending upon the extent of rotation of the shaft 5.

Since the dog does not always have an opportunity to drop into full engagement with the tooth only the 30 points of the tooth and the dog engage and are apt to be broken by the shock. In order to avoid this objection and possible breakage, I provide means for insuring that engagement of a dog with the ratchet disk shall not take place until the rider lifting the dog to inoperative position has moved a distance of at least one tooth 35 of the disk beyond the end of the shield-plate. If such means is not provided, there is a possibility that when the shield-plate is moved very slightly the rider will over-travel the shield plate by a very small amount. 40 as the lever 4 moves forward, resulting in the dog dropping into slight engagement with the tip of a tooth, moving the disk a very short distance as the engine-driven lever starts back, and almost immediately being thrown out of engagement with the tooth by the 45 rider engaging the edge of the shield-plate.

One form of the mechanism which I have devised for securing this result is shown in Figs. 12 and 13, although the same result may be obtained by many other forms. In the form shown in these figures the 50 rider 17 is provided with a spring blade 17^a securely attached thereto and formed as shown in Fig. 12, carrying at the free end thereof an auxiliary rider 17^b which normally engages the surface of the shield-plate at a point in advance of the rider 17. As the lever 4 55 swings to the right and the rider 17 passes over the edge of the shield-plate 20, the dog 15 is held in inoperative position until the auxiliary rider 17^b drops off the end of the shield-plate and permits the dog to engage the disk. As the lever 4 swings back to the left the 60 projection 17^c carried on auxiliary rider 17^b, as shown in Fig. 13, passes underneath the lug 17^d on the shield-plate and the dog 15 is not lifted out of engagement with the disk until the rider 17 encounters the edge of the shield-plate. The result of this arrangement is that 65 the dog 15 does not engage the ratchet disk 20 unless

the end of the rider 17 has passed beyond the edge of the shield-plate a distance equal to the width of a tooth on the disk, thereby insuring that the dog will completely engage with the tooth of the ratchet disk.

Since the lever 4 is normally disconnected from the valve actuating shaft 5, it is necessary that some sort of locking means be provided to maintain the valve actuating shaft in the position in which it is left when the dogs 15 and 16 are lifted out of engagement with the ratchet disk 20 by the action of the shield plate 22. 70

The form of mechanism which I have shown for accomplishing this result is disclosed in Figs. 1, 2 and 4, in which a controlling arm 23, rigidly mounted on the shaft 5, has an extension 24, the outer surface of which is made in the form of an arc with the shaft 5 as the 80 center and which swings within a locking casing 25 having a surface in the form of an arc concentric with the circle described by the outer surface of the extension 24. As shown in Fig. 4, the extension 24 is provided with oppositely disposed inclined guides 26 with 85 which co-operate balls or rollers 27 and 28, normally forced toward the position shown in Fig. 4 by adjustable springs 29 mounted in recesses in the extension 24. The inclined guides 26 are so related to the locking casing 25 that when the balls or rollers are in the position 90 shown in Fig. 4 they are in engagement with the guides and with the locking casing, and thereby lock the controlling arm 23 against movement in either direction. The ratchet disk 20, which is loosely mounted on the shaft 5, has a lug 30 extending through a slot between 95 the guides 26, the length of which slot is greater than the width of the lug, the outer end of the lug being formed to engage either of the balls or rollers 27 and 28 when the lug is moved to either end of the slot. The parts are so proportioned that when the lug is moved 100 clockwise in the direction of the arrow in Fig. 4, the lower end thereof engages the ball or roller 27 and moves it along the inclined guide 26 out of engagement with the locking casing before the lug comes into engagement with the end of the slot between the guides 26, thereby leaving the controlling arm 23 free to move in the direction of the arrow. After the arm has been unlocked, the lug 30 engages the wall at the end of the slot between the inclined guides 26, thereby rigidly connecting the ratchet wheel 20 with the controlling 110 arm 23 and moving the valve actuating shaft 5. As soon as the pressure of the ratchet wheel 20 upon the shaft 5 is relieved the ball or roller 27 is forced back to locking position by the action of the spiral spring 29, and the controlling arm is locked in the position in 115 which it was left when the ratchet wheel 20 ceased to actuate it. The same operation, of course, takes place when the ratchet disk 20 is moved counter clockwise, such movement causing the ball or roller 28 to move out of locking position, thereby permitting the controlling arm 23 to be moved in a direction opposite the 120 arrow.

The connections by means of which the load responsive device alters the position of the shield-plate 22 are shown in Figs. 1 and 2. A spur gear 31, rigidly attached to the ratchet disk 20, and moving therewith, is mounted on the shaft 5, concentrically with a rack 32 in the form of a section of an internal gear mounted on the shield plate. An idler pinion 33 meshes with the gear 31 and the rack 32 and is carried on a governor arm 130

34 loosely mounted on the shaft 5 and controlled through a link-work 35 from the governor or speed responsive device 36. Since the ratchet wheel 20 and spur gear 31 are normally stationary, the movement of the governor arm 34 and the pinion 33 in either direction causes a movement of the shield plate 22 in the same direction to permit either the dog 15 or 16 to drop into operative relation with the ratchet disk and cause a movement of the ratchet disk 20 and thereby a movement of the valve actuating shaft 5.

If the speed of the turbine decreases, the shield plate 22 is moved to the left in the direction of the arrow in Fig. 1, and as the lever 4 oscillates to the right the rider 17 drops off the end of the shield and permits the dog 15 to drop into engagement with the ratchet disk 20. The dog slides over the ratchet teeth until the lever 4 reaches the end of its travel, and as the lever 4 begins to move back toward the left, the dog 15 engages the ratchet disk and moves it. The first movement of the ratchet disk drives the ball 28 back into inoperative position, thereby releasing the controlling arm 23, and the lug 30 on the ratchet wheel 20 then engages the controlling arm 23 and moves it and the shaft 5. The rotation of the ratchet disk 20 is transmitted to the spur gear 31, rigidly attached thereto, and the rotation of the spur gear is transmitted through the idler pinion 33 to the rack 32. The relation of the gearing is such that a rotation of the spur gear 31 in the direction of the arrow causes a movement of the shield 22 in the opposite direction; and the rate of movement of the shield is the same as that of the ratchet wheel 20. The result of this arrangement is that when the dog 15 engages the disk 20 and moves it in the direction of the arrow, the shield plate 22 begins to move in the opposite direction toward the rider 17 and at the same rate as the shaft 5 is being moved by the ratchet disk. When the rider 17 engages the shield 22, the dog 15 is lifted out of engagement with the ratchet disk, the ball 28 is returned to locking position by the spring 29 and the controlling arm 23 is instantaneously locked in the position occupied by it when the dog 15 is disengaged from the ratchet disk 20. If, therefore, the dog 15 moves four teeth beyond the end of the shield plate and then begins to move the ratchet disk in the direction of the arrow, the shield plate 22 will move in the opposite direction to meet the dog, and the shield plate will move the distance of two teeth to the left while the ratchet disk is moving the distance of two teeth to the right. Since the dog is lifted to inoperative position when the rider meets the shield plate 55 the net result will be a movement of the valve actuating shaft 5 equal to two teeth of the ratchet wheel. The next oscillation of the lever 4 to the right will carry the dog 15 two teeth beyond the end of the shield plate and the same operation will be repeated, the result this time being the movement of the valve actuating shaft 5 a distance of one tooth of the ratchet disk 20 in the same direction as before and the return of the shield plate 22 to normal position. The lever 4 furnishes the power not only for actuating the shaft 5, but also for returning the shield plate 22 to normal position, so that the only work required of the governor is that necessary to shift the governor arm 34 to a position depending upon the load on the turbine.

The relation of the parts of the governing device under varying conditions, is shown in Figs. 7 to 11 includ-

sive. Fig. 7 shows the rocker arm in mid position and the shield 22 in normal position, while Fig. 8 shows the rocker arm in its extreme position to the right with the shield still in normal position. Fig. 11 shows the rocker arm in its extreme position to the left with the shield 70 in normal position. It is evident from these figures, therefore, that under normal conditions, neither of the pawls 15 or 16 engages the ratchet wheel. In Fig. 9, however, the shield 22 has been moved to the left to such an extent that the pawl 15 moves over two teeth 75 of the ratchet wheel when the rocker arm 4 reaches its extreme position to the right; while Fig. 10 shows the rocker arm returning from its extreme position to the right with the lifter 17 reaching the edge of the shield 22 and about to move the pawl 15 to inoperative position. 80

When a plurality of regulators or valves control the flow of fluid to the turbine, the spiral arrangement of the teeth 7, 7^a on the valve actuating shaft 5 may cause all of the valves to be either open or closed and disconnected from the valve controller, or one valve may be in some intermediate position and under positive control. If a sudden increase of load occurs, the valve controller 5 is moved rapidly through the proper distance, and a number of valves depending on the extent of movement of the valve actuating shaft 5 will be opened to the full extent quickly and in succession, while the last valve moved, assuming that the load is not satisfied by a given number of open valves, will be locked at some point between its open and closed positions, whereby the flow of fluid is quickly and accurately adjusted to the load on the turbine. When the load decreases the reverse operation takes place. If desired, the teeth on the rock shaft may be set in such relation to each other that several valves are in an intermediate position at the same time, at either the same or varying distances from open or closed positions, thereby throttling a plurality of inlet ports instead of one. 95

My invention may be applied to any type of prime 105 mover using motive fluid, but is particularly adapted to turbines to which it is preferably applied in the manner shown in Fig. 11, in which the turbine casing 37 is provided with a port or opening 38 which in turn has a partition 39, thereby forming two parallel discharge 110 nozzles for delivering motive fluid to the buckets of the turbine-wheel 40. In this arrangement one valve controls two discharge nozzles, but it is apparent that one valve can control either one nozzle or a plurality of nozzles, and that a plurality of such valves may be 115 used on a single turbine for controlling the inlet to the turbine and also the passage of fluid through the various stages, if the turbine is multi-stage, and that all the valves may be controlled from one actuating mechanism. 120

In accordance with the provisions of the patent statutes, I have described the principle of operation of my invention, together with the apparatus which I now consider to represent the best embodiment thereof; but I desire to have it understood that the apparatus 125 shown is only illustrative, and that the invention can be carried out by other means.

What I claim as new and desire to secure by Letters Patent of the United States, is,—

1. In a governing mechanism, the combination of valves 130

- controlling the passage of fluid, an actuator for each valve, a toothed disk for moving the actuators which is common thereto, a constantly vibrating lever, means for transmitting motion from the lever to the disk, a device responsive to load changes for controlling the action of said means which causes it to impart a step-by-step movement to the disk, and mechanism actuated by the disk which decreases the length of the steps as the disk is moved under the control of the device to cause the valves to more nearly satisfy the load conditions. 5
10. In a governing mechanism, the combination of a plurality of valves controlling the passage of fluid, an actuator for opening and closing each of said valves, a toothed disk common to the actuators and valves, a shaft common to the disk and actuators, an oscillating lever for rocking the shaft, dogs carried by the lever arranged to move the disk in one direction or the other in response to load changes, a shield plate pivotally supported on said shaft and controlling said dogs, connections between the disk and shield-plate for causing any movement of the disk to simultaneously move the shield-plate, a speed responsive device, and a connection between the speed responsive device and the shield-plate. 15
15. In a governing mechanism, the combination of a valve for controlling the passage of fluid, a toothed disk for opening and closing the valve, a constantly vibrating member, dogs carried by said member and arranged to engage the teeth on the disk, a shield-plate responsive to changes in load for controlling the action of the dogs on the toothed disk, a support for said shield-plate, and connections between the disk and shield-plate for causing any movement of the disk to simultaneously move the shield-plate to reset the shield-plate after the valve has been moved. 20
20. In a governing mechanism, the combination with a valve for controlling the passage of fluid, a toothed disk for opening and closing the valve, a constantly vibrating member, oppositely acting dogs carried by said member, one being arranged to move the disk in one direction step by step and the other to move it in the opposite direction step by step, a device responsive to speed changes for controlling the action of both dogs, and connections between the disk and shield-plate for causing any movement of the disk to simultaneously move the shield-plate to restore said device to normal position after the valve has been moved. 25
25. In a governing mechanism, the combination of valves arranged to control the passage of fluid, a toothed disk, means for opening and closing the valves successively, a vibrating member, oppositely acting dogs carried by said member and arranged to engage the teeth of said member and move it step by step, a movably-supported shield-plate for controlling the action of the dogs, connections between the disk and shield-plate for causing any movement of the disk to simultaneously move the shield-plate, a shaft governor, and a connection between the shaft governor and the shield-plate for moving said plate. 30
30. In a governing mechanism, the combination of a plurality of valves for controlling the passage of motive fluid, an actuator for each valve, a shaft common to said actuators, the actuators being arranged to open and close the valves in predetermined order, a toothed disk mounted on the shaft for moving it step-by-step in one direction or the other to meet the load conditions, a source of power, means mounted on the shaft for imparting from said source to the toothed disk a step-by-step motion and decreasing the length of the steps as the disk is moved and the valves more nearly satisfy the load conditions, and a device responsive to changes in speed for controlling the action of said means. 35
35. In a governing mechanism, the combination of a plurality of valves controlling the passage of motive fluid, an actuator for each of the valves, a shaft common to the actuators, a toothed disk mounted on the shaft for moving all of the actuators, a vibrating lever freely moving about the axis of the shaft, dogs carried by the lever which are arranged to engage the teeth on the disk and move it in one direction or the other as the load changes, a shield-plate movable about the axis of the shaft for controlling the action of the dogs in response to changes in speed, and connections between the disk and the shield-plate for caus- 40
- ing any movement of the disk to simultaneously restore the shield-plate to normal position after one or more of the valves have been moved. 45
4. In a governing mechanism, the combination of an admission valve, a toothed disk for opening and closing the valve, a member which has a to and fro motion for moving the disk, a shield-plate for controlling the action of said member on the valve, a speed responsive device for controlling the action of the shield-plate, and connections between said disk and shield-plate for causing any movement of the disk to simultaneously move the shield-plate to restore it to normal position after the valve has been moved in response to changes in speed. 50
5. In a governing mechanism, the combination of a plurality of valves for regulating the passage of motive fluid through a turbine, a device which has a constant to-and-fro movement, a toothed member, means for transmitting motion from the device to the member, a common actuating means for the valves driven by said member, mechanism responsive to load changes which controls the connection between the device and the toothed member and causes the device to impart a step-by-step movement to the member, and means actuated by the member which varies the length of the steps and makes the extent of each step a definite proportion of the extent of the other steps. 55
6. In a governing mechanism, the combination with a regulator moved to control the apparatus, of an actuating mechanism disconnected from the regulator in either extreme position thereof, said mechanism engaging the regulator to positively control it between said extreme positions and to lock it stationary at any intermediate point. 60
7. In a governing mechanism, the combination with a regulator moved to control the apparatus, of an actuating mechanism disconnected from the regulator in either extreme position thereof, said mechanism engaging the regulator to positively control it between said extreme positions and to lock it stationary at any intermediate point, and a controller regulating the extent of movement of said regulator from either extreme position. 65
8. In a governing mechanism, the combination of an admission valve, a toothed disk for opening and closing the valve, a member which has a to and fro motion for moving the disk, a shield-plate for controlling the action of said member on the valve, a speed responsive device for controlling the action of the shield-plate, and connections between said disk and shield-plate for causing any movement of the disk to simultaneously move the shield-plate to restore it to normal position after the valve has been moved in response to changes in speed. 70
9. In a governing mechanism, the combination of a plurality of valves for regulating the passage of motive fluid through a turbine, a device which has a constant to-and-fro movement, a toothed member, means for transmitting motion from the device to the member, a common actuating means for the valves driven by said member, mechanism responsive to load changes which controls the connection between the device and the toothed member and causes the device to impart a step-by-step movement to the member, and means actuated by the member which varies the length of the steps and makes the extent of each step a definite proportion of the extent of the other steps. 75
10. In a governing mechanism, the combination of a plurality of unbalanced valves each of which has a tendency to sudden movement both in opening and closing, a member common to the valves having a movement greater than is required to move a single valve, devices for positively connecting each valve to said member, said devices being in action only when one or more valves are being moved between extreme positions, and a governor controlled means for moving the said member in response to load changes. 80
11. In a governing mechanism, the combination with a regulator moved to control the apparatus, of an actuating mechanism disconnected from the regulator in either extreme position thereof, said mechanism engaging the regulator to positively control it between said extreme positions and to lock it stationary at any intermediate point. 85
12. In a governing mechanism, the combination with a regulator moved to control the apparatus, of an actuating mechanism disconnected from the regulator in either extreme position thereof, said mechanism engaging the regulator to positively control it between said extreme positions and to lock it stationary at any intermediate point, and a controller regulating the extent of movement of said regulator from either extreme position. 90
13. In a governing mechanism, the combination with a regulator moved to control the apparatus, of an actuating mechanism disconnected from the regulator in either extreme position thereof, said mechanism engaging the regulator to positively control it between said extreme positions and to lock it stationary at any intermediate point, and a load responsive device regulating the extent of movement of said regulator from either extreme position. 95
14. In a governing mechanism, the combination with a plurality of regulators moved to control the apparatus, of an actuating mechanism moving said regulators in succession and disconnected from each regulator in either extreme position thereof, said mechanism engaging each of said regulators to positively control it between said extreme positions and to lock it stationary at any intermediate point. 100
15. In a governing mechanism for turbines, the combination with a plurality of regulators moved to control the turbine, of an actuating mechanism moving said regulators in succession and disconnected from each regulator in either extreme position thereof before engaging the next said mechanism engaging each of said regulators to positively control it between said extreme positions and to lock it stationary at any intermediate point. 105
16. In a governing mechanism for turbines, the combination with a regulator moved to control the turbine, of an actuating member, connected to the regulator only while

exerting pressure thereon to move it and disconnected therefrom when the pressure is relieved, and a lock holding the regulator when disconnected.

17. In a governing mechanism for turbines, the combination with a regulator moved to control the turbine of an actuating member moving said regulator and releasing it at any point of its travel, and a lock holding said valve at the point of release.

18. In a governing mechanism for turbines, the combination with a regulator moved to control the turbine of an actuating member moving said regulator, release mechanism disconnecting the actuating member and the regulator at any point of the travel thereof, a lock holding the regulator at the point of release, and a load responsive device controlling the action of the release mechanism.

19. In a governing mechanism for turbines, the combination with a valve controlling the flow of fluid to the turbine, of an actuating member moving said valve step by step and releasing the valve at each step, and a lock holding said valve at the point of release.

20. In a governing mechanism for turbines, the combination with a valve controlling the flow of fluid to the turbine, of an actuating member moving said valve step by step and releasing the valve at each step, a load responsive device controlling the amplitude of each step, and a lock holding said valve at the point of release.

21. In a governing mechanism for turbines, the combination with a valve moved to control the turbine, of a valve actuator for operating the valve, a lock normally holding said valve actuator against movement, an actuating member and clutching mechanism moved by the actuating member to release the lock and then rigidly connect the actuating member and the valve actuator.

22. In a governing mechanism for turbines, the combination with a regulator moved to control the turbine, of an actuating member connected to the regulator only while in motion and disconnected therefrom upon coming to rest, and a lock for holding the regulator when disconnected said lock being released when the actuating member is in connection with the regulator.

23. In a governing mechanism, the combination with

coöperating members one of which is toothed, one of said members being continuously moving and the other connected to a movable regulator, of a speed responsive controller moved to permit engagement of said members and disengaging them when the regulator has been moved, and restraining means preventing engagement of said members unless said controller moves so as to leave said members in engaging relation during a relative movement thereof of more than one tooth of the toothed member.

24. In a governing mechanism, the combination with a toothed disk and a dog coöperating therewith, one continuously oscillating and the other connected to a movable regulator, of a speed responsive controller moved to permit said dog to engage said disk and disengaging the dog from the disk when the regulator has been moved, and restraining means connected to the dog and engaging the controller to hold the dog out of engagement with the disk unless the controller moves so as to leave the dog in engagement with the disk during a relative movement of dog and disk of more than one tooth.

25. In a governing mechanism, the combination with a toothed disk connected to a movable regulator, of an oscillating member carrying a dog to engage and move said disk, a disengaging member connected to the dog, a speed responsive controller normally coöperating with said disengaging member to hold the dog out of engagement with the disk and moved to permit said oscillating member to carry the dog beyond the end of the controller and into engagement with the disk, and a rider engaging the controller to hold the dog out of engagement when moving in one direction but not in the other and permitting engagement of the dog and disk only when the distance between the edge of the controller and the disengaging member equals a predetermined amount.

In witness whereof, I have hereunto set my hand this second day of February, 1907.

JOHN G. CALLAN.

Witnesses:

JOHN A. McMANUS, Jr.,
HENRY O. WESTENDARE.
